GLOW DISCHARGE SWITCH

Daniel Johannes Hindericus Admiraal, Eindhoven, Netherlands, assignor to General Electric Company, a corporation of New York

Application December 5, 1946, Serial No. 714,217
In the Netherlands February 13, 1946

7 Claims. (Cl. 200—113.5)

1

This invention relates to electric discharge devices of the type employing ionizable mediums such as gases or vapors, and more particularly to a thermal glow discharge switch for starting and operating said devices.

Heretofore, thermal glow discharge starter devices or switches with at least one bimetallic actuated electrode were used as switches for controlling the starting of fluorescent discharge lamps having filamentary electrodes which require heating before starting a discharge therebetween. When a suitable potential is first applied to the switch, a glow discharge starts therein which heats a bimetallic member and causes it to flex. The flexing of the bimetallic member brings the switch contacts or electrodes into engagement to extinguish the discharge in the switch. Current flows through the electrodes of the lamp which are connected in series across the terminals of a current source by the switch. No further heat is generated in the glow discharge device or switch after the switch contacts engage each other. Thus, the heat sensitive parts of the starter device cool off and its contacts separate again. This cooling off occurs rather rapidly so that the filamentary electrodes of the fluorescent discharge lamps may be insufficiently heated to support an electric discharge therebetween in spite of the fact that when the contacts of the glow discharge device open an extra voltage surge is generated by a reactor connected in series with or parallel to the fluorescent discharge lamp. As a result of this condition, the starter device repeats its starting attempts until the electrodes of the fluorescent discharge lamp have reached that temperature necessary to support an electric discharge. The repeated attempts to ignite the fluorescent discharge lamp by means of insufficiently heated electrodes are detrimental to the life of these electrodes, and the light flashes occurring therewith are undesirable for lighting purposes.

An object of my invention is to provide a new and improved glow discharge switch which will provide the necessary time delay in the application of the starting voltage to insure an adequate initial heating of the electrodes of the electric discharge device.

Another object of my invention is to provide a new and improved glow switch including therein a pair of bimetallic members having different temperature-deflection characteristics and which support contacts and which flex in the same direction to contact one another, one of said members being of shorter length and constructed of thinner

2

laminations than the other whereby it possesses a greater unit deflection but smaller absolute deflection than the said other member.

A further object of my invention is to provide a new and improved glow switch including therewith a pair of bimetallic actuated contacts which when heated by the glow discharge move in the same direction, engage each other, and remain in engagement with each other over a part of the return motion during the cooling period.

Further features and advantages of my invention will appear from the following detailed description of species thereof.

Referring to the figure, the discharge device 15 therein comprises an elongated tubular or cylindrical envelope 2 having sealed into the ends thereof thermionic electrodes 3 and 4 which may be of the filamentary type each herein illustrated as comprising a coil, preferably in the form of a coiled coil of tungsten wire suitably activated, as example, with a usual mixture of barium and strontium oxides. The envelope 2 contains an ionizable medium. This ionizable medium may comprise a rare gas like krypton, neon, argon or mixtures thereof at a pressure of a few millimeters and a small quantity of mercury which, during operation of the lamp, has a low pressure of the order of ten microns. The device 1 may be a low pressure positive column lamp of the fluorescent type with a suitable phosphor which under the influence of an electric discharge through the ionizable medium produces fluorescence.

The device 1 is connected in series with a suitable ballast impedance in the form of a choke 35 coil 5 and a starting switch 6 and connected across a suitable source of alternating current 7, 7'.

The starting or heating circuit 8 embodies starting switch 6 in series with filamentary electrode 3, glow discharge device or switch 9, filamentary electrode 4, and choke coil 5. A capacitance 10 of 0.01 microfarad rating is preferably connected directly across the glow discharge device or switch 9 and the device 1.

The glow discharge device or switch 9 comprises a hermetically sealed glass envelope 11, a pair of electrode structures 12 and 13 affording an electric discharge supporting surface and comprising thermally responsive bimetallic members 14 and 15, respectively welded to support wires 16 and 17, and an ionizable gaseous atmosphere therein such as neon at a pressure of 40 mm. at room temperature. A pair of suitable contacts such as tungsten contacts 18 and 19 mounted perpendicular to each other are fastened by suitable means to the ends of the bimetallic mem-

bers 14 and 15 respectively. The gap between these contacts at room temperature is about 0.75 mm.

In accordance with my invention, both electrodes of the glow discharge switch contain bimetal members which are mounted in such a manner and are of such dimensions that the contacts when the electrodes are heated by the glow discharge move in the same direction, engage each other and remain in engagement with each other over a part of the return motion during the cooling period as well as during part of the motion during heating.

This can be accomplished by making the bimetallic member of the electrode structure, which is in front in the sense of the motion that is caused by the heating, shorter and thinner than the bimetallic member of the other electrode structure. Thus, by means of varying the lengths of the bimetallic members the displacement arc through which the free ends of the members move may be varied. By this means, the electrode structures are made to engage each other. If the shorter bimetallic member is also thinner than that of the other bimetallic member it will have a greater coefficient of deflection, cool off quicker after engagement, and create an equal or greater force on the return travel than the longer bimetallic member. A means thereby is provided for the contacts to remain in engagement over part of the return motion during the cooling period. In this arrangement, it is advantageous if the shorter bimetallic member which is provided with a contact constitutes the free moving end of one electrode structure and is approximately one half the length and 15 per cent thinner than the bimetallic member constituting part of the other electrode structure. For example, in a glow switch containing neon at a pressure of 40 mm. at room temperature the longer bimetallic member 14 may be 11 by 4 by 0.2 mm. and the shorter bimetallic member 15 may be 5 by 2 by 0.15 mm. in size and spaced between contacts a distance of 0.75 mm. at room temperature.

When the main switch 6 is closed, a glow discharge exists between electrode structures 12 and 13. The glow discharge may be aided by use of an activated surface such as one employing an oxide of an alkaline earth metal on at least one of the electrodes. This glow discharge causes the bimetallic members 14 and 15 to flex in the same direction. The thickness of the laminations of member 14, however, is larger than that of member 15, so that the change in shape of member 14 per unit length is less than that of member 15. The length of member 14 is, however, so much greater than that of member 15 that the end of member 14 approaches engagement with member 15 after a travel of a few millimeters and thus the contacts 18 and 19 engage each other. Thus, the opposite sides of the current source 7, 7 for the filamentary electrodes 3, 4 are conductively connected through the glow discharge switch 11, and limited by the reactor or choke coil 5. After engagement of the contacts 18 and 19 the glow discharge becomes short circuited, thereby the bimetallic members 14 and 15 loose their source of heat and begin to cool off. The thinner member 15 cools more rapidly than the thicker member 14 so that the member 15 applies a pressure upon the member 14 and continues to do so over a part of the return travel of the electrode structures. When the contacts 18 and 19 separate, the fila-

mentary electrodes 3 and 4 have reached a sufficiently high temperature to support a discharge therebetween. For example, at a line voltage of 225 volts, the contacts 18 and 19 remain in engagement with each other for about two seconds. The glow discharge which precedes the engagement in this example lasts about two seconds.

The above described starting device offers advantages over and beyond the prior art arrangements. In many of the prior art devices, a contact corresponding to contact 19 is supported directly by the longer supporting wire 17 without the mounting of bimetallic member 15 in between and the contacts 18 and 19 are separated about 1.5 mm. at room temperatures. When this glow discharge device of this conventional construction is used, the glow discharge lasts about 2 seconds until the contacts touch for the first time. The glow discharge device remains closed for about 0.1 second and after that repeats with a frequency of about 80 per minute until the discharge tube 1 ignites. During the time these repetitions occur, light flashes take place and radio reception in the neighborhood of the installation is disturbed by strong crashes, in spite of the presence of capacitor 10. When my glow discharge device is used, only one click can be heard when the contacts open.

It is obvious that the repeat ignition voltage of the glow discharge devices in both cases has been chosen larger than the operating voltage of the discharge tube 1 so that no glow discharge will take place in the glow discharge devices after the tube is ignited.

35 What I claim as new and desire to secure by Letters Patent of the United States is:

1. A glow switch of the discharge type comprising an envelope containing an ionizable medium and a pair of laminated bimetallic members each having a discharge supporting surface, one of said members being substantially longer than the other and constructed of thicker laminations to produce rapid engagement between the members upon establishment of a glow discharge therebetween and to effect engagement therebetween during at least a part of the return travel during the cooling period by virtue of the difference in the respective temperature-deflection characteristics.

50 2. A glow switch of the discharge type comprising an envelope containing an ionizable medium and a pair of laminated bimetallic members each having a discharge supporting surface and supporting a contact, one of said members being substantially one half the length of the other bimetallic member and constructed of thinner laminations to produce rapid engagement between the members upon establishment of a glow discharge therebetween and to effect engagement between the contacts during at last a part of the return travel during the cooling period by virtue of the difference in respective temperature-deflection characteristics.

65 3. A glow switch of the discharge type comprising an envelope containing an ionizable medium and a pair of laminated bimetallic members each having a discharge supporting surface and supporting a contact, one of said elements being substantially shorter than the other bimetallic member and constructed of at least 15 per cent thinner laminations to produce rapid engagement between the members upon establishment of a glow discharge therebetween and to effect engagement between the contacts during at least a part of the return travel during the cooling period

y virtue of the difference in respective temperature-deflection characteristics.

4. A glow switch of the discharge type comprising an envelope containing an ionizable medium and a pair of laminated bimetallic members each having a discharge supporting surface and carrying a contact, one of said members being substantially one half the length of the other bimetallic member and constructed of at least 15 per cent thinner laminations to produce rapid engagement between the members upon establishment of a glow discharge therebetween and to effect engagement between the contacts during at least a part of the return travel during the cooling period by virtue of the difference in respective temperature-deflection characteristics.

5. A glow switch of the discharge type comprising an envelope containing neon at a pressure of 40 mm. at room temperature and a pair of laminated bimetallic members each having a discharge supporting surface and carrying a contact, one of said members being substantially longer than the other and constructed of thicker laminations to produce rapid engagement between the members upon establishment of a glow discharge therebetween and to effect engagement between the contacts during at least a part of the return travel during the cooling period by virtue of the difference in the respective temperature-deflection characteristics.

6. A glow switch of the discharge type comprising an envelope containing an inert gas and a pair of lead-in wires supporting a pair of laminated bimetallic members each having a discharge supporting surface and carrying a contact, one of said members being substantially longer than the other and constructed of thicker lamina-

tions to produce rapid engagement between the members upon establishment of a glow discharge therebetween and to effect engagement between the contacts during at least a part of the return travel during the cooling period by virtue of the difference in the respective temperature-deflection characteristics.

7. A glow switch of the discharge type comprising an envelope containing neon at a pressure of 40 mm. at room temperature and a pair of lead-in wires supporting a pair of laminated bimetallic members each having a discharge supporting surface, one of said members being 11 by 4 by 0.2 mm. in size and the other 5 by 2 by 0.15 mm. in size and the contact distance between members being 0.75 mm. at room temperature, to produce rapid engagement between the members upon establishment of a glow discharge therebetween and to effect engagement between the members during at least a part of the return travel during the cooling period by virtue of the difference in the respective temperature-deflection characteristics.
